UNITED STATES PATENT OFFICE.

FRANKLIN JOSEPH DESHLER, OF SANTA ANA, CALIFORNIA.

RAFTER-CUT-MARKING TOOL.

Application filed October 18, 1923. Serial No. 669,352.

To all whom it may concern:

Be it known that I, FRANKLIN JOSEPH DESHLER, a citizen of the United States, residing at Santa Ana, in the county of Orange and State of California, have invented certain new and useful Improvements in Rafter-Cut-Marking Tools; and I do declare the following to be a full, clear, and exact description of the invention, such as will enable others skilled in the art to which it appertains to make and use the same.

My invention relates to tools for marking the proper cuts for common rafters, jacks, cripples, valley jacks, etc., and while I am aware that numerous devices have been provided for this purpose, the majority of them have been of such complicated construction and have included such intricate scales, charts and the like, as to be practically of no value, unless used by a well educated workman. It is the object of my invention however to provide an exceptionally simple tool which is free of the objections above pointed out, yet will be extremely accurate.

With the foregoing in view, the invention resides in the novel subject matter herein-after described and claimed, the description being supplemented by the accompanying drawings.

Figures 1 and 2 are respectively a side elevation and an edge view of the tool in position upon a rafter.

Figure 3 is a transverse sectional view as indicated by line 3—3 of Fig. 1.

Figure 4 is a detail sectional view on line 4—4 of Fig. 1.

Figure 5 is a detail section through one of the positioning devices which engage the edge of a rafter being marked, as indicated by line 5—5 of Fig. 1.

Figure 6 is a sectional view on line 6—6 of Fig. 5.

Figure 7 is an elevation of one of the wings which are used for marking the edges of the rafters.

Figure 8 is a sectional view on line 8—8 of Fig. 7.

In the drawings above briefly described, the numeral 1 designates a flat blade adapted to extend across either side of a rafter and provided with a straight edge 2 along which the side of the rafter is to be marked. Extending rigidly from one end of the blade 1, and projecting obliquely from the edge 2 of said blade, are two arms 3 which diverge from each other and extend in oppo-

site directions from the blade 1. These arms are preferably provided with attaching portions 4 secured against opposite sides of the blade 1, by screws, rivets, or other suitable fasteners 5, and in the construction shown, each arm 3 is provided with a longitudinal slot 6.

Contacting with the inner sides of the arms 3, are two flat wings 7 which diverge from the marking edge 2 and are themselves provided with marking edges 8, either one of which is adapted to extend across one edge of a rafter, for marking the line of cut. In the construction shown, the wings 7 are provided with slots 9 transverse to the slots 6, and clamping bolts 10 having suitable wing-nuts 11, are passed through said slots to clamp the wings against the arms, while permitting adjustment of said wings into different angular relations with the blade 1.

A clamp 12 is mounted adjustably upon the edge of the blade 1, remote from the marking edge 2, and this clamp is provided with portions 13 at opposite sides of the blade, either one of which is adapted to contact with the edge of a rafter, according to the side of the latter against which the blade is positioned. The function for these portions will be hereinafter described.

At the end of the blade 1, adjacent the arms 3, I have shown a projecting ear 14, to which a clip or the like 15 is pivoted by a suitable clamping bolt 16, said clip carrying an arm 17 which is positioned in a plane through the center of the tool, such plane being parallel with the opposite sides of the blade 1. The free end of the arm 17 is preferably flattened and widened as indicated at 18, so that it may engage the edge of a rafter upon which the tool is used. The function of this arm will also be described hereinafter.

The device is exceptionally easy to operate. First, the carpenter locates the proper plumb line for a rafter of desired pitch, such line being drawn across one side of the rafter. Then, the blade 1 is positioned against the rafter with the straight edge 2 disposed along said line. This having been done, the clamp 12 is adjusted until one of its portions 13 comes in contact with the edge of the rafter. Then, the arm 17 is swung inwardly until its end 18 contacts with the rafter, it being understood that both parts 12 and 17 are tightly clamped in

the position to which they are moved. Then, by loosening the proper nut 11, the wing 7 extending across the edge of the rafter, may be adjusted until the marking edge 8 contacts with said edge of the rafter, throughout its length. Then, the nut is again tightened. The entire tool is then transferred to the other side of the rafter and the other projecting portion 13 is placed against one edge of the latter, as is also the portion 18 of the arm 17. Then, the other wing 7 is properly adjusted and the tool is thus in readiness for accurately marking the necessary guide lines across the side of any rafter and its edge.

I have found that with a single set of wings 7, I am enabled to mark rafters for any pitch roof, up to one-half pitch. For steeper roofs, another set of wings must be substituted for the wings 7.

It will be seen from the foregoing that practically no trouble is experienced in properly setting the tool for marking any of the various cuts on the numerous kinds of rafters used. Furthermore, the invention is unusually simple and hence, rather inexpensive and is not liable to get out of adjustment when once firmly set.

Excellent results have been obtained from the details disclosed and they are therefore preferably followed, but within the scope of the invention as claimed, numerous minor changes may be made.

I claim:

35 1. A rafter cut marking tool comprising a blade provided with a marking edge, a pair of rigid converging arms extending from one end of said blade and having flat sides in planes oblique to the sides of said 40 blade, and flat wings held against said flat sides of said arms and having marking edges extending obliquely to the marking edge of said blade for marking rafter edges.

45 2. A rafter cut marking tool comprising a blade provided with a marking edge, a pair of rigid converging arms extending from one end of said blade and having flat sides in planes oblique to the sides of the blade, flat wings contacting slidably with said flat 50 sides of said arms and having marking edges extending obliquely to the marking

edge of said blade for marking rafter edges, and means for clamping said wings against said arms in different adjusted positions.

3. A rafter cut marking tool comprising 55 a blade provided with a marking edge, a rigid arm extending from said marking edge and having a flat side in a plane oblique to the sides of said blade, and a flat wing contacting slidably with said flat side of said arm and having a marking edge extending obliquely to the marking edge of said blade for marking an edge of the rafter, said wing and blade having angularly related slots, and clamping means passing through said 60 slots for securing the wing to the arm in any 65 adjusted position.

4. A rafter cut marking tool comprising a blade having a marking edge, a pair of wings diverging from said marking edge 70 and extending obliquely from the opposite sides of said blade, said wings having marking edges extending obliquely to the marking edge of said blade for marking an edge of the rafter, and rafter-engaging positioning means carried by the tool and extending oppositely from a plane through the center 75 thereof.

5. A rafter cut marking tool comprising a blade having a marking edge, a pair of 80 wings diverging from said marking edge and extending obliquely from the opposite sides of said blade, said wings having marking edges extending obliquely to the marking edge of said blade for marking 85 an edge of the rafter, a rafter-engaging positioning device adjustably carried by and extending laterally in opposite directions 90 from said blade, and another rafter-engaging positioning device adjustably carried by the tool in spaced relation with the first named device, said other device having a portion extending laterally in opposite directions from a plane through the center 95 of the tool.

6. A structure as specified in claim 5: 100 said other positioning device consisting of an arm and means pivotally and adjustably connecting the same with said blade.

In testimony whereof I have hereunto affixed my signature.

FRANKLIN JOSEPH DESHLER.
